UNITED STATES PATENT OFFICE.

LEWIS WOLFLEY, OF PRESCOTT, ARIZONA TERRITORY.

CONCRETE PILING AND PRODUCTION THEREOF.

No. 910,252.

Specification of Letters Patent.

Patented Jan. 19, 1909.

Application filed August 19, 1907. Serial No. 389,255.

To all whom it may concern:

Be it known that I, LEWIS WOLFLEY, a citizen of the United States, residing at Prescott, in the county of Yavapai and Territory of Arizona, have invented certain new and useful Improvements in Concrete Piling and Production Thereof, of which the following is a specification.

My invention relates to concrete piling formed in position from mortar in a fluid or plastic state; and to the production of such piling, in which a tube or casing, preferably in sections, is first placed for the reception of the mortar and afterwards removed, leaving the pile completely formed.

The invention has for one of its objects the more ready and efficient production of piles from concrete or other material capable of hardening and which, when set or hardened, forms a durable body such as concrete.

A further object is to make the piles more compact and more firmly set in the surrounding earth.

A further object is to facilitate the depositing of mortar or other material within the tube or casing, especially when the piles are being made in wet ground or under water.

A further object is to construct a series or sheet of piling composed of individual piles united or formed in the process of making into a continuous sheet or wall.

The piling formed in accordance with my invention is particularly suitable for levees, breakwaters, sea piers, foundations on land and under water, and in fact for all purposes for which wooden or separate individual concrete piles have been used.

Further objects will more fully appear as I proceed with the description of the invention.

The invention consists in the novel features of concrete piling and method of making same hereinafter described, and illustrated in the accompanying drawings, in which—

Figure 1 is a view showing in vertical section my improved method of making piles, several of the completed piles being shown in elevation. Fig. 2 is a horizontal section showing a series or sheet of piling. Fig. 3 is a horizontal section, on a larger scale, of two tubes or casings, showing the interlock for keeping the same in alinement. Fig. 4 is a vertical section through one of these tubes or casings, showing the interlock and a method of connecting the sections. Figs. 5

and 6 are similar views, respectively, of a modification of the same.

Referring to the drawings, and first particularly to Fig. 1 thereof, A is a hollow pile-tube or casing, preferably in sections, hereinafter termed the casing, which is sunk in any suitable way to the required depth in the earth to form a hole for the pile. A number of such casings are shown, designated as A, A', A², A³, A⁴. I prefer to sink the casing, as shown at A, by means of a water-jet, and for this purpose employ a nozzle B having a diameter nearly equal to the internal diameter of the casing and connected by pipe b with a source of water under pressure (not shown). The lower face of the nozzle is preferably convex and perforated, so as to project jets downwardly and outwardly, and pipe b is of such length that the nozzle may be kept at or near the bottom of the casing. As the casing is sunk, the material will pass upwardly outside of the casing and very little, if any, water will escape into the casing. After the casing has been sunk to the proper depth, the material which is to form the concrete is introduced into the upper end of the casing. Heretofore it has been the practice to permit the material, usually composed of a mixture of cement, sand, gravel, broken stone, and water, to fall to the bottom of the casing. This, however, dissociates the ingredients and, if water is present in the casing (as is likely when the work is being carried on in wet ground or under water) washes the cement coating from the solid parts so that only a weak and inferior concrete, if any, is formed. In accordance with my invention, I lower a given mass of material bodily and deposit it at the bottom of the casing, so that the mixture remains intact. To effect this I employ a dump bucket C of any suitable construction but preferably, as shown, consisting of a body-portion increasing in diameter from top downward, and a drop bottom c controlled by a latch c'. This bucket will not be further described in detail here, as it forms the subject of a separate application. In lowering the bucket when the latch c' strikes the bottom within the casing, or the material already deposited, the bottom section c is released and the load dumped, when the bucket may be withdrawn empty. The work may thus be carried on rapidly without dissociation or disintegration of the material. In some instances, es-

pecially where long piles are to be made, I prefer to make the casing in sections suitably jointed, as by screw-threads, as shown at a , in Figs. 1 and 4. Pipe b is then also divided into similar sections.

In the formation of a single pile, the casing is sunk to the required depth and a hole formed in any suitable way. The bucket containing material to form the concrete pile is then lowered into the casing, and on reaching the bottom, the material is deposited and the bucket withdrawn. The casing is then partially withdrawn far enough to discharge most of the mortar into the hole. The material is then pressed or tamped to force it into the interstices of the surrounding earth and form a compact mass. These operations are repeated until the pile is completed. As the sections of the casing rise above the ground or water level they are disconnected and removed, thus avoiding the necessity of raising the mortar the full height of the emerged casing before lowering it therein.

In the formation of a series of piles, such as in the making of a levee, it is desirable not only that the individual piles should be placed close together, but in order to prevent "undermining" they should be firmly and directly united so as to form a "concrete sheet-piling", or unbroken line of piles. In order to effect this I employ a plurality of casings, as shown in Fig. 1, which are sunk into the ground close to or in contact with each other, and in such alignment as to form the desired contour or direction of the sheet of piling. The casings A , A' , A'' , A^3 , A^4 show various stages in the progress of making the piling, but not necessarily the actual arrangement of the work.

I preferably first sink a number of casings and form holes, as indicated at A' , Fig. 1, the number of these casings being optional but preferably sufficient to allow space for the sinking gang and the filling gang to work without interference, and to prevent the newly set piling from being broken by sinking a casing adjoining it. A complete pile is then formed in the first casing, as hereinbefore described, or in any suitable way, this pile contacting with the adjoining casing. Such a pile is indicated at D' . The next individual pile is then formed by introducing concrete material into and withdrawing the next casing, as hereinbefore described. The tamping or pressing of this material forces it into the interstices of the surrounding earth, and into contact with the next casing in advance. It is also forced into intimate contact with the adjacent formed pile, the concrete material of which has not yet been set, and firmly unites therewith. Under the pressure, the material spreads slightly, to form what might be termed a connecting part or web d between

the adjacent piles, uniting them into a continuous sheet. It is not necessary to completely form the first pile before beginning the second of the series, as the second may be begun just after and follow the first. As casings are removed from completed piles they are reset at the advance end of the line, and again used as described. In some cases I may have several piles in the line under construction at the same time.

It is sometimes difficult to drive or sink the casings in alignment and cause them to be side by side throughout their length, and in such cases I provide interlocking guides for the casings which, as shown in Figs. 80 3 and 4, comprise a tongue E riveted or otherwise secured to one side of the casing, and a groove F secured to the other side. These interlock with the groove and tongue, respectively of adjacent casings, so that the proper continuity of the structure is assured. When a curved sheet of piling is required, casings with these interlocking devices placed at different angular positions, or suitably modified, are provided. The tongues and groove are of course so arranged as not to interfere with the screw-thread or other connection of the casing sections, as shown in Fig. 4.

In Figs. 5 and 6 I have shown a modified arrangement of interlocking devices and section connection. Here two tongues are provided spaced at such a distance apart that when interlocked with the grooves H , H of an adjacent casing the sides of the casing will approach very closely or contact with each other, so as to facilitate the union of the adjacent piles. In Fig. 6 I have also shown a bayonet joint connection for the casing sections, in which a reduced end a' of one section fits into the adjacent end of the other section where it is secured by a pin a^2 engaging slot a^3 . There are as many of these parts cooperating as are necessary for strength and when in the locked position the tongues and grooves of the sections will always be in alignment.

Many other changes and modifications may be made without departing from the spirit of the invention. For instance, different modes of sinking the casings and removing the earth from the interior thereof may be employed; the casings need not be round or circular as shown, but may be of any desired cross section; the exact sequence of operations is not essential in every aspect of the invention; and various changes may be made in the details of the apparatus and method without departing from the invention.

By the term "concrete material" as used in this specification and claims, I intend to include any fluid or plastic material capable of hardening and suitable for the purpose described.

Having thus described my invention, what I claim as new, and desire to secure by Letters Patent of the United States, is—

1. The method of making concrete piling which consists in molding a sheet of individual piles in place, withdrawing the molding means each pile being united to the adjacent pile by the pile material when the molding means is withdrawn, and permitting said material to harden.
2. The method of making concrete piling which consists in sinking a plurality of tubes or casings into the ground in close proximity to each other, introducing concrete material in a fluid or plastic state into said tubes or casings, and withdrawing said tubes or casings to permit said material of each to discharge and unite with the material from an adjacent tube or casing.
3. The method of making concrete piling which consists in sinking a plurality of tubes or casings into the ground in close proximity to each other, forming a pile from concrete material by means of and withdrawing a tube or casing, then forming another pile in contact with the first pile by means of and withdrawing an adjacent tube or casing, and permitting the material of said piles to unite and set.
4. The method of making concrete piling which consists in sinking a sectional tube or casing, forming a pile from fluid or plastic material therein, slowly withdrawing said tube or casing to permit said material to discharge at its lower end, and removing the sections from the upper end of said tube or casing as they reach a predetermined level.
5. The method of making concrete piles which consists in sinking a sectional tube or casing into the ground to the proper depth, removing the earth from the interior of the

tube or casing, introducing concrete material into the tube or casing, partly withdrawing the tube or casing to permit the material to discharge at its lower end, and detaching sections of the tube or casing as they reach a predetermined level.

6. The method of making a series or sheet of concrete piling which consists in separately molding individual piles in place and causing the adjacent piles to be connected by the union of the pile material.

7. The method of making a series or sheet of concrete piling which consists in separately molding individual piles in place and causing the material of adjacent piles to merge and form an integral uniting web.

8. The method of making concrete piling which consists in sinking a plurality of tubes or casings into the ground in close proximity to each other, forming a pile from concrete material by means of and withdrawing a tube or casing, introducing a limited amount of said material into an adjacent tube or casing, partly withdrawing this tube or casing to permit the material to discharge at its lower end, and pressing or tamping said material to compact the same in contact with the adjacent pile.

9. The method of making concrete piling which consists in sinking a sectional tube or casing, introducing concrete material therein, withdrawing said tube or casing, and removing the sections from the upper end of said tube or casing as they reach a predetermined level.

In testimony whereof I affix my signature, in presence of two witnesses.

LEWIS WOLFLEY.
